NONSPILLING PAINT PALETTE

Joseph P. di Gemma, Brooklyn, N. Y.

Application September 30, 1950, Serial No. 187,743

4 Claims. (Cl. 41—5)

1

This invention relates to paint palettes, such as those used by artists. It has particular reference to an improved paint palette embodying separate compartments for paint pigments and a liquid vehicle, the compartments being so arranged as to prevent spilling or intermixing of colors when the palette is tilted from a horizontal position.

The equipment commonly used by artists includes the ordinary flat palette and a separate paint box. While efforts have been made to combine a palette and a paint box in a unitary assembly, by attaching some form of palette to the paint box, the results have not been satisfactory. For example, in such prior combinations the control of the water or other liquid vehicle for the pigments has been difficult and awkward due to the tendency of the paint to flow freely over the palette or to spill over when the box is tilted or moved.

An object of the present invention, therefore, is to provide an artist's palette having separate compartments for the pigment and liquid vehicles, which is so arranged that the liquid vehicle and the pigments will not overflow or run when the palette is tipped.

A further object is to provide a palette of the character described which will minimize waste of paint.

Another object is to incorporate the palette and compartments for the pigments and the liquid vehicle into a single unit which can be managed with one hand while it is in use, without danger of unintentional mixing of the materials, and which is of simple and inexpensive construction.

A paint palette made in accordance with the invention comprises walls extending vertically from a horizontal wall or base and forming therewith a series of adjacent compartments for liquid vehicles. A flange extends continuously around the upper portion of each compartment and projects inward from the vertical walls thereof to form a retainer for the liquid vehicle when the palette is tilted from a horizontal position, the flanges forming top openings for the respective compartments. The palette also comprises other vertical walls forming pigment compartments separate from the liquid vehicle compartments but accessible through the top openings of the latter. Preferably, the top flanges of the several compartments are formed by a lattice which is supported on the vertical walls of the palette. If desired, the vertical walls forming the pigment compartments may also be provided with retaining flanges at their upper portions

and extending inward into the pigment compartments where they are accessible through the top openings of the liquid vehicle compartments.

For better understanding of the invention, reference may be had to the accompanying drawings in which:

Fig. 1 is a plan view of a preferred form of the new palette;

Fig. 2 is a vertical-sectional view of the palette illustrated in Fig. 1;

Fig. 3 is a view similar to Fig. 2 but showing the palette tilted from a horizontal position;

Fig. 4 is a perspective view of the palette, and

Fig. 5 is a vertical-sectional view of a carrying case, showing the palette mounted in the case.

Referring to the drawings, the new palette comprises a base 1 having near one of its corners a thumb hole 2 for holding the palette when it is in use. The base 1 forms the bottom wall of a series of adjacent compartments 3, the sides of which are formed by vertical walls 4 extending upward from the base. Additional vertical walls 5 are arranged in each compartment to form a sub-compartment 6 for a paint pigment. Accordingly, the walls 1, 4 and 5 form pigment compartments 6, one for each shade of paint to be employed, and a compartment 3 adjacent each pigment compartment. The compartments 3 contain the water or other liquid vehicle 13, 14, 15 and 16, and may also be used as mixing surfaces for the corresponding paints before they are applied by the artist.

A lattice 7 is supported on the vertical walls 4 and forms a flange extending continuously around the upper portion of each compartment 3. The continuous flange 7 of each compartment projects inward from the vertical walls thereof to form a retainer for the liquid vehicle when the palette is tilted from a horizontal position, as shown in Fig. 3. If desired, the flat area on top of the lattice structure 7 may be used as a palette for mixing the colors when a substantial amount of liquid is maintained in the compartments. The flanges 7 formed by the lattice should be of uniform width and should overhang each compartment 3 by an amount approximately equal to the overhang of the flanges of the adjacent compartments. The flanges 7 form top openings 8 for the respective compartments 3, to provide access to the liquid vehicles in these compartments. As shown, the openings 8 also provide access to the pigments in the pigment compartments 6 adjacent the liquid compartments.

Retaining flanges 9 are provided at the upper

portions of the vertical walls 5 and extend inwardly into the pigment compartments 6 at the regions where these compartments are accessible through the openings 8. The flanges 9 serve to prevent spilling of the paint due to tilting of the palette, when the paint is in liquid form, as shown at 17, 18 and 19. Of course, when the pigment is solid, as is the case with some water colors, the retainer lips or flanges 9 may be omitted.

A deeper central compartment 10 is provided for the main supply of water or other liquid vehicle 11 for the pigment, the compartment 10 serving as a reservoir for the liquid to be added to the paint compartments. For convenience of refilling, emptying, and the like, the compartment 10 is slidably fitted into an aperture in the base 1 and the lattice 7 so that it can be removed by pushing it up in the body of the apparatus. When the compartment 10 is replaced, it is held in position by projection 12 which rests on the top of a vertical retaining wall 4a.

The apparatus of the invention can be fabricated from sheet metal or it can be manufactured from plastic or other suitable material. If desired, the compartments 3 and 6 may be made of cylindrical or other form instead of the generally square form as illustrated. Also, the base 1 may be arranged at the top of the structure so that it can be combined with the lattice 7, in which case the bottoms of the several compartments are formed independently of the base.

It will be observed that the new palette can be tilted and even shifted to a perpendicular position without spilling or intermixing any of the liquids, as shown in Figs. 3 and 5. Also, the palette is well adapted to be fitted into a carrying case 29, as shown in Fig. 5, where it may be carried in an upright position by a handle 21.

I claim:

1. A paint palette comprising horizontal and

vertical walls forming a series of adjacent compartments for liquid vehicles, a flange extending continuously around the upper portion of each compartment and projecting inward from the vertical walls thereof to form a retainer for the liquid vehicle when the palette is tilted from a horizontal position, the flanges forming top openings for the respective compartments, and vertical walls forming pigment compartments separate from said first compartments but accessible through said openings.

2. A paint palette according to claim 1, in which said flanges are formed by a lattice supported on said vertical walls.

3. A paint palette according to claim 1, comprising also retaining flanges at the upper portions of the vertical walls of the pigment compartments and extending inward into said last compartments where they are accessible through said openings.

4. A paint palette according to claim 1, comprising also a liquid receptacle removably mounted on the palette and projecting below the bottom thereof.

JOSEPH P. DI GEMMA.
